UNITED STATES PATENT OFFICE

164,380

COMBINED POTATO MASHER AND MEAT TENDERIZER

Milton R. Packer, Detroit, Mich.

Application June 21, 1950, Serial No. 10,665

Term of patent 3½ years

(Cl. D44—29)

To all whom it may concern:

Be it known that I, Milton R. Packer, a citizen of the United States and a resident of the city of Detroit, county of Wayne, State of Michigan, have invented a new, original, and ornamental Design for a Combined Potato Masher and Meat Tenderizer, of which the following is a specification, reference being had to the accompanying drawings, in which:

Fig. 1 is a perspective view of my combined potato masher and meat tenderizer showing my new design;

Fig. 2 is a bottom elevational view thereof;

Fig. 3 is a top elevational view thereof;
Fig. 4 is a side elevational view.

I claim:
The ornamental design for a combined potato masher and meat tenderizer, as shown.

MILTON R. PACKER.
